(57) **CLAIM**

The ornamental design for a tap handle as shown and described.

DESCRIPTION

FIG. 1 is a perspective view of a tap handle, showing my new design;

FIG. 2 is an elevational view of the front of the tap handle;

FIG. 3 is an elevational view of the rear of the tap handle;

FIG. 4 is a left side elevational view of the tap handle;

FIG. 5 is a right side elevational view of the tap handle;

FIG. 6 is a top plan view of the tap handle; and,

FIG. 7 is a bottom plan view of the tap handle.

The broken line showing is included for the purposes of illustrating portions of the article and its placement, and forms no part of the claimed design.
